UNITED STATES PATENT OFFICE.

GEORGE R. LONG, OF WATERBURY, CONNECTICUT, AND HENRY G. CORDLEY, OF GLEN RIDGE, NEW JERSEY, ASSIGNORS TO CORDLEY & HAYES, OF NEW YORK, N. Y., A CORPORATION OF NEW YORK.

SELF-CLOSING FAUCET.

Application filed December 1, 1920. Serial No. 427,560.

To all whom it may concern:

Be it known that we, GEORGE R. LONG, a citizen of the United States, residing at Waterbury, in the county of New Haven and

5 State of Connecticut, and HENRY G. CORDLEY, a citizen of the United States, residing at Glen Ridge, in the county of Essex and State of New Jersey, have invented certain new and useful Improvements in Self-Closing Faucets, of which the following is a description, reference being had to the accompanying drawings, forming a part hereof.

Our invention relates to self closing faucets and has for its object to provide a faucet 15 of the turning plug type which will be simple and inexpensive in construction, readily assembled and disassembled, in which a single spring serves both to return the turning plug to closed position and to hold the plug 20 in its seat so as to take up wear and prevent leakage. A further object is to provide the faucet with means by which the turning plug may be rotated to open position by pressing against it the glass or other receptacle into 25 which liquid is to be drawn.

With the object above described and other objects hereinafter explained in view our invention consists in the construction and combination of elements hereinafter described and claimed.

Referring to the drawings;

Figure 1 is a front view of a faucet embodying our invention;

Figure 2 is a side view of the same;

35 Figure 3 is a longitudinal central sectional view of the casing, turning plug and cap assembled;

Figure 4 is a central cross sectional view of the faucet;

40 Figure 5 is a cross sectional view through the cap;

Figure 6 is a view of the cap, casing and plug separated the cap and casing being shown in longitudinal section and the plug being shown in elevation; and

45 Figure 7 is an end view of the turning plug.

In the drawings 1 indicates the casing in which the turning plug 2 rotates. The casing is provided on one side with a connecting tube, here shown as tapered, internally screwthreaded at 4 for attachment to the container for the liquid to be drawn off through the faucet, and the casing has a

discharge opening 5 in its underside and a 55 port or opening 6 in its upper part communicating with the interior of the connecting tube 3.

The casing is open at one end and tapers from this open end to an abutment 7 near the 60 other end having a central cylindrical opening 8 through it. Surrounding the opening 8 and extending rearward from the abutment 7 is an annular flange 10 having its exterior diameter substantially less than the 65 exterior diameter of the casing so as to leave about its base an annular shoulder 11 the exterior diameter of which is less than that of the exterior of the casing so as to leave about its base a bearing 12 for the end of the 70 wall or flange 14 of the cap.

13 indicates a cap having a flange or wall 14 adapted to fit over the exterior of the annular shoulder 11 and bear at its end against the bearing 12, and having a central cylindrical projection 15 adapted to fit within and turn freely in the central opening 8 in the end of the casing. Through the centre of this cylindrical projection 15 extends an opening 16 flattened on one side or otherwise made non-cylindrical at its inner end. In the flange or wall 14 of the cap is formed a slot 17 extending parallel with the end of the cap to receive the stop pin 18 carried by an arm 19 secured to the casing. A coiled 80 spring 20 is arranged in the annular space between the exterior of the cylindrical projection 15 and the interior of the wall or flange 14 of the cap, one end of the spring extending into an opening 21 in the bearing 90 12 of the casing and the other end extending into an opening 22 in the wall or flange 14 of the cap near the end of the cap. The spring is so constructed that it tends to expand in a direction parallel with the axis 95 of the faucet and to also expand in a direction outward from the axis. By its tendency to expand in a direction parallel with the axis of the faucet it acts to force the end of the cap away from the casing and thus, 100 through the construction hereinafter explained, draws the turning plug into its seat, and by its tendency to expand outward from the axis it acts to force its ends apart and thus to rotate the cap in a direction to turn 105 the plug 2 to closed position.

The turning plug 2 is tapered to fit the tapered seat formed in the casing and has

at its inner end a central cylindrical projection 25 flattened on one side to fit the opening 16 in the cylindrical projection 15 of the cap, and having in its end a 5 screwthreaded opening to receive a screw 26. This screw 26 is provided with an enlargement 27 which fits and turns freely in a central recess 28 in the outer end of the cap and bears at its inner end against the shoulder 10 29. The screw is provided with a milled head 30. This screw 26 holds the plug and the cap together so that as the spring 20 presses the cap outward away from the casing it will draw the plug with it and 15 thus force the plug into its seat with a yielding pressure.

Through the turning plug 2 extends, at right angles to its axis, an opening 31 so arranged that its lower end may be brought 20 into register with the discharge opening 5 and with its other end leading to a recess 32 extending across the plug at right angles to its axis and adapted to be brought into communication with the port or opening 6 25 to admit liquid from the connecting tube 3.

On its outer end the turning plug is provided with an operating handle having a depending portion 35 extending radially from the line of the axis of the turning plug 30 and preferably in a downward direction, and a portion 36 extending from the outer end of the portion 35 parallel with the axis of the turning plug and towards the other end of the faucet so as to be, when the turning plug is in closed position, directly below the discharge opening 5. By pressing the rim of a glass or other receptacle into which liquid is to be drawn against this portion 36 the handle may be swung rearward to turn 40 the turning plug into open position and permit liquid to flow into the glass or other receptacle.

It will, of course, be understood that the length of the spring 20 is such, and the stop 45 opening 17 is so arranged that when the stop 18 is in the opening 17 the spring is under tension sufficient to hold the rear end of the stop opening against the stop and thus hold the turning plug in closed position, that is with the lower end of the opening 31 out of 50 line with the discharge opening 5. When the handle is swung rearward as above described, the rotation of the turning plug puts the spring 20 under further tension 55 and, when the handle is free to swing forward, the spring acts to rotate the turning plug back to initial position causing the turning plug to reassume its closed position.

60 The arm 19 which carries the stop pin 18 is preferably arranged to fit between lugs 35 and 36 on the exterior of the casing and is secured in position by a screw 37.

The slot or opening 17 is formed of sufficient width relative to the diameter of the

stop pin 18 to permit the cap to move towards and away from the casing slightly so as to draw the turning plug into its seat.

Having thus described our invention what we claim is:

1. In a self-closing faucet the combination of a casing having a tapered seat for the turning plug open at one end and having an inlet and discharge port, a turning plug extending into the tapered seat in the casing having an opening through it at right angles to its axis having its lower end adapted to be brought into and out of register with the discharge opening by rotation of the plug, a cap carried by the casing on the end opposite its open end and rotatable thereon, a spring within the cap expandable in a direction parallel with the axis of the casing, and means for holding the cap and turning plug together so that outward movement of the cap will draw the turning plug into its seat.

2. In a self-closing faucet the combination of a casing having a seat for the turning plug open at one end and having an inlet and discharge port, a turning plug extending into the seat in the casing having an opening through it at right angles to its axis having its lower end adapted to be brought into and out of register with the discharge port by rotation of the plug, a cap carried by the casing on the end opposite its open end and rotatable thereon, a spring within the cap having one end secured to the casing and the other end secured to the cap and expandable in a direction radial to the axis of the casing, and means for so connecting the cap and turning plug that they will rotate together.

3. In a self-closing faucet the combination of a casing having a tapered seat for the turning plug open at one end and having an inlet and discharge port, a turning plug extending into the tapered seat in the casing having an opening through it at right angles to its axis having its lower end adapted to be brought into and out of register with the discharge port by rotation of the plug, a cap carried by the casing on the end opposite its open end and rotatable thereon, a spring within the cap having one end secured to the casing and the other end secured to the cap, expandable in a direction radial to the axis of the casing and also expandable in a direction parallel with the axis of the casing, and means for so connecting the cap and turning plug that they will rotate together and so that outward movement of the cap will draw the turning plug into its seat.

4. In a self-closing faucet the combination of a casing having a tapered seat for the turning plug open at one end and having an inlet and discharge port, a turning plug extending into the tapered seat in the cas-

ing having an opening through it at right angles to its axis having its lower end adapted to be brought into and out of register with the discharge port by rotation of the 5 plug, a cap carried by the casing on the end opposite its open end and rotatable thereon, a spring within the cap having one end secured to the casing and the other end secured to the cap, expansible in a direction radial to the axis of the casing and also expansible in a direction parallel with the axis of the casing, means for so connecting the cap and turning plug that they will rotate together and so that outward 10 movement of the cap will draw the turning plug into its seat, and means for limiting the rotation of the cap.

5. In a self-closing faucet the combination of a casing having a seat for the turning 15 plug open at one end and having an inlet and discharge port, a turning plug extending into the seat in the casing having an opening through it at right angles to its axis having its lower end adapted to be 20 brought into and out of register with the 25

discharge opening by rotation of the plug, a cylindrical opening in the end of the casing opposite its open end of less diameter than the seat for the turning plug, an annular flange surrounding said opening, a cap for 30 the end of the casing having a central cylindrical projection fitting within the annular flange and opening in the end of the casing and having a central opening through it having a non-circular portion, a central 35 non-circular projection on the end of the turning plug fitting within the non-circular opening in the cylindrical projection of the cap, means for securing the cap to the central projection of 40 the turning plug, and a spring surrounding the annular flange of the casing having one end secured to the cap and the other end secured to the casing so as to rotate the cap relative to the casing by its expansion. 45

In testimony whereof, we affix our signatures this 26th day of November, 1920.

GEORGE R. LONG.
HENRY G. CORDLEY.
